GAUGE PLATE FOR RAILWAY SURFACE TRACKS

Vito Carone, Los Angeles, Calif.

Application June 7, 1943, Serial No. 490,002

5 Claims. (Cl. 238—332)

This invention relates to a gauge plate for railway surface tracks, and it is primarily an object of the invention to provide a device of this kind which comes in contact only with one rail of a trackway, thereby requiring no insulation and thus eliminating signal failures often caused by faulty insulation.

It is also an object of the invention to provide a gauge plate of this kind embodying an assembly which can be installed without necessitating removal of the tie and without requiring the boring of holes into or through the tie and also wherein the assembly is one permitting an unlimited number of adjustments of the rail without relocating or resetting of the plate assembly.

A still further object of the invention is to provide a gauge plate of this kind which can be readily placed between or outside of rails to hold such rails, either straight or curved, in place, and wherein the assembly is of a type to be easily installed by one man.

The invention also has for an object to provide a gauge plate embodying an assembly of a character which requires no maintenance or repairs other than occasional oiling and wherein the assembly is of a type to be manufactured without requiring precision machinework of any kind.

The invention consists in the details of construction and in the combination and arrangement of the several parts of my improved gauge plate for railway surface tracks whereby certain important advantages are attained, as will be hereinafter more fully set forth.

In order that my invention may be better understood, I will now proceed to describe the same with reference to the accompanying drawings, wherein:

Figure 1 is a view in top plan illustrating a gauge plate constructed in accordance with an embodiment of my invention and in applied position.

Figure 2 is a sectional view taken substantially on the line 2—2 of Figure 1.

Figure 3 is an enlarged sectional view taken substantially on the line 3—3 of Figure 1.

Figure 4 is an enlarged detailed sectional view taken substantially on the line 4—4 of Figure 1.

Figure 5 is a view in perspective of one of the parts herein embodied, unapplied, and

Figure 6 is a fragmentary view in perspective of one end portion of the cross bar as herein included.

As disclosed in the accompanying drawings, 1 denotes an elongated flat bar to be placed trans-

versely across a tie T and of a length to extend a desired distance beyond the opposite sides of the tie. Each end portion of the bar 1 is provided with a reverted or inwardly disposed part 2 terminating in a depending foot 3 having close contact with a side face of the tie T. This reverted part 2 is substantially parallel with the adjacent end portion of the bar 1 proper and spaced therefrom a desired distance, the outer extremities of the bar 1 and the reverted part 2 being connected by the intermediate short arm 4.

Disposed from above through each extended portion of the bar 1 and through the central portion of the reverted or returned part 2 is a headed member or bolt 5 held against displacement by a cotter pin 6 disposed through the lower or free end portion of the member or bolt 5 below the reverted or returned part 2.

The bar 1 is anchored to the tie T by the spikes 7 or the like which extend through the central portion of the bar 1 and penetrate the tie T.

Each of the bolts 5 serves as a pivot for a flat arm 8, said bolt 5 being freely disposed through a laterally directed lug 9 carried by the central portion of the arm 8. The inner end of this arm 8 closely approaches a side face of the tie T and said inner end is provided with a depending arm 10 substantially at right angles thereto and which has its lower end provided with an inwardly disposed foot 11 which underlies the tie T immediately adjacent thereto.

The outer extremity of each of the arms 8 is continued by an outwardly and downwardly inclined arm 12 disposed on an angle of approximately 45 degrees with respect to the arm 8 and one marginal portion of this arm 12 is provided with an upstanding ear 14 provided with a central opening 15. Freely insertable through the opening 15 of each of the ears 14 is the threaded end portion 16 of an elongated shank 17 provided at its opposite end with an inwardly facing hook 18 which engages from below the outer flanges 19 of the rail R comprised in a surface trackway. The shank 17 has its outer end portion underlying the rail.

The threaded portion 16 of each of the shanks 17 outwardly of the associated ear 14 has engaged thereon a nut 20 which has direct contact with the ear 14. Upon tightening of the nut 20, the arms 8 will swing on the pivot bolts 5 in a direction toward the rail R causing the arms or legs 10 to grip the sides of the tie and thereby hold the assembly securely in place. This tightening of the nuts 20 also, through the medium of the

shank 17, will draw the rail 19 to desired gauge or location.

It is believed to be clearly apparent that when the assembly as herein embodied is in place on a tie T and the hooks 18 of the shanks or rods 17 are engaged over the outer flange 19 of the rail R of a trackway and the nuts 20 have been properly tightened, the bar 1 cannot move in any direction. The arms 12 are disposed on an outward and downward incline to assure the shanks or rods 17 being below the top surface of the tie T to permit its ready passage or placement under the rail R in a straight line and also to eliminate a stumbling hazard.

It is believed to be apparent from the foregoing that the assembly as herein disclosed is one which comes only in contact with one rail R, thereby requiring no insulation and thus eliminating signal failures caused by faulty insulation and which can be readily installed without removing or otherwise interfering with the tie and wherein it is not required to bore any holes into or through the tie.

It is also believed to be obvious that an unlimited number of adjustments can be made without relocating or resetting of the assembly and that the assembly is one which can be readily placed between or outside of rails and which can be employed to advantage to hold in place straight or curved rails, switches, frogs, slips, guard rails and the like. It is believed to be equally apparent that the assembly can be installed by one man and requires no maintenance or repairs except probably for an occasional oiling.

From the foregoing description it is thought to be obvious that a gauge plate for railway surface tracks constructed in accordance with my invention is particularly well adapted for use by reason of the convenience and facility with which it may be assembled and operated.

What is claimed is:

1. A gauge plate assembly comprising a bar to be rested across the tie of a trackway and of a length to extend beyond the opposite sides of the tie, arms pivotally connected with the extended portions of the bar and having parts for contact with the sides of the tie upon swinging of said arms in one direction, elongated rods freely disposed through a part of the arms and having hooks to engage the flange of a rail remote from the applied bar, and means carried by the rods and coacting with the arms for drawing the rods and for swinging the arms in a direction toward the rails.

2. A gauge plate assembly comprising a bar to be rested across the tie of a trackway and of a length to extend beyond the opposite sides of the tie, arms pivotally connected with the extended portions of the bar and having parts for contact with the sides of the tie upon swinging of said arms in one direction, elongated rods freely disposed through a part of the arms and having hooks to engage the flange of a rail re-

mote from the applied bar, and means carried by the rods and coacting with the arms for drawing the rods and for swinging the arms in a direction toward the rails, the portions of the arms 5 with which the rods are freely engaged being downwardly disposed to bring said rods below the upper face of the tie.

3. A gauge plate assembly comprising a bar to be placed transversely on a tie and of a length 10 to extend beyond opposite sides of a tie, the outer extremities of the bar being provided with reverted portions terminating in feet for contact with the side faces of the tie, arms associated with the opposite end portions of the bar, each 15 of said arms having a lug extending between the adjacent end portion of the bar and the reverted portion thereof, a member disposed through said parts of the bar and through the lug for mounting the arm for swinging movement relative to 20 the adjacent side face of the tie, an ear carried by each of the arms and angularly related thereto, an elongated rod having an end portion freely disposed through the ear and provided with a hook to engage over the flange of a rail, and 25 a member threading upon the rod outwardly of the ear for contact with the ear to draw the rod and to swing the arm toward the rod, the inner portion of the arm engaging the adjacent side face of the tie upon such swinging movement.

4. A gauge plate assembly comprising a bar adapted to be disposed transversely upon a tie, arms, means for pivotally connecting said arms to the bar at points spaced on said bar a distance 30 sufficient to position said arms at opposite sides of the tie upon which the bar is placed, the arms having swinging movement relative to the adjacent side faces of the tie, outstanding ears carried by the outer end portions of the arms, rods 35 freely disposed through said ears and having hooks to engage over the flange of a rail, and members threaded upon the rods outwardly of the ears for contact with the ears to draw the rods and to swing the arms to bring the inner 40 ends of the arms into contact with the side faces of a tie.

5. A gauge plate assembly comprising a bar adapted to be disposed transversely upon a tie, arms, means for pivotally connecting said arms to the bar at points spaced on said bar a distance 50 sufficient to position said arms at opposite sides of the tie upon which the bar is placed relative to the adjacent side face of the tie, outstanding ears carried by the outer end portions of the 55 arms, rods freely disposed through said ears and having hooks to engage over the flange of a rail, members threaded upon the rods outwardly of the ears for contact with the ears to draw the rods and to swing the arms to bring the inner 60 ends of the arms into contact with the side faces of a tie, and depending arms carried by the inner ends of the first arms.

VITO CARONE.
